UNITED STATES PATENT OFFICE.

VINCENT BENDIX, OF CHICAGO, ILLINOIS, AND HENRY E. VAN NESS, OF ELMIRA, NEW YORK; SAID VAN NESS ASSIGNOR OF HIS RIGHT TO ECLIPSE MACHINE COMPANY, OF ELMIRA, NEW YORK, A CORPORATION OF NEW YORK.

ENGINE-STARTER.

1,274,372.

Specification of Letters Patent.

Patented Aug. 6, 1918.

Application filed November 8, 1916. Serial No. 130,225.

To all whom it may concern:

Be it known that we, VINCENT BENDIX, of Chicago, Cook county, Illinois, and HENRY E. VAN NESS, of Elmira, Chemung county, New York, have invented certain new and useful Improvements in Engine-Starters, of which the following is a specification.

Our invention relates to a starter for an engine such as a gas engine, and the object thereof is to provide a simple, efficient and reliable device of this character to be operated by a prime mover of any kind, such for instance as an electric motor.

Our starter embodies as a material part of its organization that type of drive or transmission exemplified in patents heretofore issued to Bendix, for instance Patent No. 1,125,935, dated January 26, 1915, and Patent No. 1,172,864, dated February 22, 1916. This type of engine starter is characterized by a prime mover (such as an electric motor or motor-generator of the two-unit and single unit starter systems respectively), and a transmission or drive for transmitting the power of the motor by means of a rotatable member, such as a screw shaft, and a driving member such as a pinion mounted thereon, for transmitting the power of the motor to some member or part of the engine to be started, such as the fly-wheel thereof.

The object of our present invention is to provide a transmission or drive of the general character described driven by a starting motor unit or by a motor generator, constructed and arranged to automatically mesh and demesh an auxiliary gear or pinion with the fly-wheel gear or other member of the engine. This special drive is, however, more particularly intended for use in connection with a motor-generator set in which a constantly rotating condition of armature shaft is presented. As shown this special transmission embodies a regular standard construction of Bendix transmission or drive and in addition a certain operating connection between that pinion and the fly-wheel of the engine. Briefly speaking, this operating connection consists of a separate pinion or gear which is operated and controlled by the pinion of the screw shaft for the purpose of meshing and demeshing the auxiliary pinion as respects the fly-wheel.

In the drawings Figure 1 is a sectional elevation on the line 1—1 of Fig. 2, looking in the direction of the arrow; Fig. 2 is a section on the line 2—2 of Fig. 1; Fig. 3 an elevation of the additional pinion or gear, and Fig. 4 an elevation of the spring cup or retainer.

The construction and mode of operation of the standard Bendix drive embodied in the organization about to be explained are the same as that illustrated in our patents aforesaid. It will therefore be sufficient to merely designate the parts by reference numerals as follows: 1 is the armature shaft, 2 is the hollow screw shaft thereon, 3 the pinion or gear screw-threaded on the screw-shaft and 4 the spring driving connection between the outer end of the shaft 1 and the driving head 2^a. A portion of the casing of the motor is indicated at A which motor may be either a single unit or a motor-generator.

The new or additional portion of this new organization of transmission or drive comprises essentially a pinion or gear operated and controlled in its movements, both rotary and longitudinal, by the pinion 3 of the standard drive, whereby such additional pinion is adapted to be meshed with and demeshed from the gear teeth 5^a of a fly-wheel 5 or other rotatable part of the engine to be started.

Describing this additional operating connection, the same comprises a stationary shaft 6 suitably supported in the motor casing and in a bracket 7. On this shaft there is mounted to slide and to rotate the additional or second pinion or gear 8, a bushing 9 being preferably provided in the central bore thereof. This pinion is held to its outer or right hand normal position, shown in Fig. 2, with a yielding pressure as by means of a coiled spring 10, one end of which is received within the circular groove 8^a of the pinion 8 and the other end within the groove 11^a of a spring retainer 11. This retainer is made of sheet metal having a central opening so as to fit upon the shaft 6 and flanged so as to bear against the outer face of the boss a and also along the outside thereof whereby such retainer is held in proper position and centered with respect to the other parts. This spring holds the pinion 8 outwardly toward the right (Fig. 2) against the edge of a sleeve 12 acting as

a stop therefor, such sleeve pressing in turn against the bushing 13 for the outer end of the shaft 6. By preference this shaft is held against rotation by means of a pin 14 passing 5 through the shaft, bushing and bracket.

It will be observed that the two pinions 3 and 8 are relatively so mounted that when the pinion 3 is advanced inwardly toward the motor, due to the rotation of the screw- 10 shaft 2, it will mesh with the pinion 8, as clearly indicated in Fig. 1 and also that after full meshing of these two pinions has taken place the weight disk 3^a of the pinion 3 will come into contact with the righthand 15 side, Fig. 2, of the pinion 8, with the result that the latter pinion will be moved longitudinally of its axis and along the shaft 6 against the tension of the spring 10, into mesh with the teeth of the fly-wheel. When 20 the pinion 3 has reached its outermost position toward the left, Fig. 2, when it can no longer move longitudinally but must rotate with the shaft, it will rotate the pinion 8 and consequently rotate the fly-wheel. 25 When the engine starts on its own power and the pinion 3 moves backwardly along the screw shaft to home position, the pinion 8 being thereupon relieved of the pressure holding it to the left against the tension of 30 the spring will move back to its home position, thereby becoming demeshed from the fly-wheel.

We claim:

1. In a drive of the character described, 35 the combination of a rotatable member, a driving member mounted thereon, a second driving member operated and controlled by the first driving member and adapted to be thereby operatively engaged with a part of 40 the engine to be started but normally out of engagement therewith, and means for holding such second driving member in normal position.

2. In a drive of the character described, 45 the combination of a rotatable member, a driving member mounted thereon, a second driving member operated and controlled by the first driving member and adapted to be thereby operatively engaged with a part of 50 the engine to be started but normally out of engagement therewith, and yielding means for holding such second driving member in normal position.

3. In a drive of the character described, 55 the combination of a rotatable member, a driving member mounted thereon, a second driving member operated and controlled by the first driving member and adapted to be thereby operatively engaged with a part of 60 the engine to be started but normally out of engagement therewith, and a spring for holding such second driving member in normal position.

4. In a drive of the character described,

the combination of a motor-driven member 65 mounted for automatic longitudinal movement when the motor is operated, a driving member mounted for rotary and longitudinal movement, and, when moved longitudinally, adapted to be engaged with a part 70 of the engine to be started, said first-named member coöperating with the driving member to move it longitudinally, the latter member being normally out of engagement with the engine part, and means for holding the driving member in such normal position.

5. In a drive of the character described, 75 the combination of a motor-driven member mounted for automatic longitudinal movement when the motor is operated, a driving member mounted for rotary and longitudinal movement and, when moved longitudinally, adapted to be engaged with a part 80 of the engine to be started, said first-named member coöperating with the driving member to move it longitudinally, the latter member being normally out of engagement with the engine part, and means for holding the driving member in such 85 normal position.

6. In a drive of the character described, 90 the combination of a motor-driven member mounted for automatic longitudinal movement when the motor is operated, a driving member mounted for rotary and longitudinal movement, and, when moved longitudinally, adapted to be engaged with a part 95 of the engine to be started, said first-named member coöperating with the driving member to move it longitudinally, the latter member being normally out of engagement with the engine part, and yielding means for holding the driving member in such 100 normal position.

7. In a drive of the character described, 105 the combination of a rotatable member, a driving member mounted thereon for rotary movement therewith and longitudinal movement thereon, a second driving member 110 which is adapted to be rotated by the first driving member and to be moved thereby into engagement with a part of the engine to be started, and means for holding the second driving member in normal position 115 and out of said engagement with the engine part.

8. In a drive of the character described, 120 the combination of a rotatable screw shaft, a pinion screw threaded thereon for rotary movement therewith and longitudinal movement thereon, a second pinion which is adapted to engage a part of the engine to be started and with which the first pinion is adapted to mesh when the screw shaft is 125 rotated, means for holding the second pinion in normal position out of such engagement with a yielding pressure, the first pin-

ion having means whereby the second pinion is moved into such engagement against such yielding pressure.

9. In a drive of the character described, 5 the combination of a rotatable screw shaft, a pinion screw threaded thereon for rotary movement therewith and longitudinal movement thereon, a second pinion which is adapted to engage a part of the engine to 10 be started and with which the first pinion is adapted to mesh when the screw shaft is rotated, a spring for holding the second pinion in normal position out of such engagement with a yielding pressure, the first pinion 15 having means whereby the second pinion is moved into such engagement against the spring pressure.

10. In a drive of the character described, the combination of a rotatable screw shaft, 20 a pinion screw threaded thereon for rotary movement therewith and longitudinal movement thereon, a second pinion which is adapted to engage a part of the engine to be started and with which the first pinion 25 is adapted to mesh when the screw shaft is rotated, and a spring for holding the second pinion in normal position out of such engagement with a yielding pressure, said second pinion being arranged in the path of 30 movement of the first pinion and moved longitudinally thereby when the latter moves longitudinally on the screw shaft.

11. In a drive of the character described, the combination of a rotatable screw shaft, 35 a pinion screw threaded thereon for rotary movement therewith and longitudinal movement thereon, a second pinion which is adapted to engage a part of the engine to be started and with which the first pinion 40 is adapted to mesh when the screw shaft is rotated, and a spring for holding the second pinion in normal position out of such engagement with a yielding pressure, said first pinion having a projection adapted to 45 contact the second pinion and to thereby move the latter longitudinally into engagement with a part of the engine to be started.

12. In a drive of the character described, the combination of a rotatable screw shaft, 50 a pinion screw threaded thereon for rotary movement therewith and longitudinal movement thereon, a second pinion which is adapted to engage a part of the engine to be started and with which the first pinion 55 is adapted to mesh when the screw shaft is

rotated, a plain shaft which is parallel with the screw shaft and on which the second pinion is loosely mounted for both rotary and longitudinal movements, and a spring 60 encircling the shaft and bearing against the second pinion to hold the latter in normal position, the second pinion being arranged in the path of the first pinion and moved thereby into engagement with a part of the engine to be started. 65

13. In a drive of the character described, the combination of a rotatable screw shaft, a pinion screw threaded thereon for rotary movement therewith and longitudinal movement thereon, a second pinion which is 70 adapted to engage a part of the engine to be started and with which the first pinion is adapted to mesh when the screw shaft is rotated, a plain shaft which is parallel with the screw shaft and on which the second 75 pinion is loosely mounted for both rotary and longitudinal movements, and a spring encircling the shaft and bearing against the second pinion to hold the latter in normal position, the second pinion being arranged 80 in the path of the first pinion and moved thereby into engagement with a part of the engine to be started, and a spring retainer mounted on the plain shaft for holding one 85 end of the spring.

14. In a drive of the character described, the combination of a rotatable screw shaft, a pinion screw threaded thereon for rotary movement therewith and longitudinal movement thereon, a second pinion which is 90 adapted to engage a part of the engine to be started and with which the first pinion is adapted to mesh when the screw shaft is rotated, a plain shaft which is parallel with the screw shaft and on which the second pinion 95 is loosely mounted for both rotary and longitudinal movements, and a spring encircling the shaft and bearing against the second pinion to hold the latter in normal position, the second pinion being arranged 100 in the path of the first pinion and moved thereby into engagement with a part of the engine to be started, the second pinion having on one side a groove to receive one end of the spring, and a spring retainer mounted on the plain shaft for holding the other end of the spring. 105
